US0D1096781S

(12) **United States Design Patent** (10) **Patent No.:** **US D1,096,781 S**
(45) **Date of Patent:** **** Oct. 7, 2025**

(54) **DISPLAY SCREEN OR PORTION THEREOF WITH GRAPHICAL USER INTERFACE**

(71) Applicant: **Apple Inc.**, Cupertino, CA (US)

(72) Inventors: **Jonathan R. Dascola**, San Francisco, CA (US); **Evgenii Krivoruchko**, San Francisco, CA (US); **Stephen O. Lemay**, Palo Alto, CA (US); **Richard D. Lyons**, London (GB); **Jay Moon**, San Francisco, CA (US); **Israel Pastrana Vicente**, Spring, TX (US); **Lorena Pazmino**, San Francisco, CA (US); **William A. Sorrentino, III**, San Francisco, CA (US); **Matan Stauber**, San Francisco, CA (US)

(73) Assignee: **Apple Inc.**, Cupertino, CA (US)

(**) Term: **15 Years**

(21) Appl. No.: **29/893,912**

(22) Filed: **Jun. 4, 2023**

(51) LOC (15) Cl. **14-04**

(52) U.S. Cl.

USPC **D14/485**

(58) **Field of Classification Search**

USPC **D14/485-495**

(57) **CLAIM**

The ornamental design for a display screen or portion thereof with graphical user interface as shown and described.

DESCRIPTION

The sole FIGURE is a front view of a display screen or portion thereof with graphical user interface showing the claimed design.

The peripheral dashed broken lines illustrate a display screen or portion thereof, and form no part of the claimed design.

The dashed broken lines within the peripheral dashed broken lines depict portions of the graphical user interface which form no part of the claimed design.

1 Claim, 1 Drawing Sheet
